CLAIM

The ornamental design for a bottle carrier, as shown and described.

DESCRIPTION

FIG. 1 is a perspective view of a bottle carrier showing my new design;

FIG. 2 is a front elevational view, with the strap broken away for the convenience of illustration;

FIG. 3 is a right side elevational view thereof;

FIG. 4 is rear elevational view thereof;

FIG. 5 is left side elevational view thereof;

FIG. 6 is a top plan view thereof;

FIG. 7 is a bottom plan view thereof; and,

FIG. 8 is a perspective view thereof in an opened condition.

The broken line showing of a bottle in FIG. 1 is for illustrative purposes only and forms no part of the claimed design;

FIG. 1

FIG. 2

FIG. 3

FIG. 4

FIG. 5

FIG. 6

FIG. 7

FIG. 8
